Attorney, Agent, or Firm—Robert Strauch; Stephen C. Strauch

[57] **CLAIM**

The ornamental design for a body sling, as shown.

DESCRIPTION

FIG. 1 is a top view of a first embodiment of a body sling showing our new design; and,

FIG. 2 is a top view of a second embodiment thereof. The bottom, right, left, front and back of the body sling form no part of the claimed design.
